TRANSFER SHEET HOLDER

Edward Hano, Holyoke, Mass.

Application January 30, 1937, Serial No. 123,251

8 Claims. (Cl. 282—3)

This invention relates to improvements in transfer sheet holders, and is designed particularly for use in co-operation with fan fold manifolding forms in counter sales books and autographic registers.

It is required in many merchandising systems that the original sales slip and a copy or two or more copies other than the original, be attached together after the sales record is made, and that this attached relation shall continue during the passage of the sales record through one or more departments of the store. This method of having two or more sales record copies attached to each other is now accomplished in salesbooks put up in bound book form and stapled or sewed together at one end, with means of putting carbons in one of the other ends or sides.

It is an object of this invention to provide means for retaining a transfer sheet, or sheets, in an autographic register or continuous form salesbook, where the sheets are not bound together in book form, but consist of an endless zig-zag pack of forms folded both longitudinally and transversely into one continuous pack and drawn over a writing plate on which are attached the transfer sheets. This form of book has, to my knowledge, never been manufactured heretofore, except by myself.

A further object of this invention is to provide, in co-operation with a writing plate or table of a counter salesbook, or autographic register, supporting means for one or more transfer sheets which will securely support and hold the transfer sheets between the upper and lower sheets of a set of folded zig-zag forms, which will also serve as a guide for the forms, and which will permit movement of the forms while retaining the transfer sheets in position.

These, and other objects and advantages of this invention, will be more completely disclosed and described in the following specification, the accompanying drawing, and the appended claims.

Broadly, this invention comprises, in co-operation with a writing plate having oppositely disposed bearing elements, two spaced strip members secured together at one end, one of the members being longer than the other, the longer of said members being adapted to be received and removably engaged in the bearing elements, and a transfer sheet provided with means for removable engagement on the shorter of said strip members.

A preferred embodiment of this invention is illustrated in the accompanying drawing, in which:

Fig. 1 is a perspective view of the transfer sheet holder.

Fig. 2 is a partial plan view of a writing plate with fan fold forms, transfer sheet, and holder in operating position thereon.

Fig. 3 is a partial plan view of a transfer sheet attached on the holder.

Fig. 4 is a cross sectional view, taken on the line 4—4 of Fig. 3.

Fig. 5 is a back or underside view of a transfer sheet engaged on the holder.

Fig. 6 is a view similar to Fig. 5 with the holder removed.

Fig. 7 is a diagrammatic view of a zig-zag folded manifold form pack.

Fig. 8 is a cross sectional view, taken on the line 8—8 of Fig. 2, and

Fig. 9 is a longitudinal sectional view, taken on the line 9—9 of Fig. 2.

Referring now to the drawing in detail, in which like numerals refer to like parts throughout:

A writing plate, or table 1 is provided with a slot 2 through which a set of zig-zag folded manifolding forms 3 may be drawn onto the plate or table 1. The forms 3 are formed from a continuous strip which is divided into individual forms by transverse lines of weakness 4 and folded on its longitudinal center line 5 to provide an upper or original sheet 6 and a lower or copy sheet 7. The writing plate 1 is also provided with oppositely disposed ears or lugs 8 formed with openings 9 for receiving tapered end portions 10 and 11 of a transfer sheet holder 12. The transfer sheet holder 12 is made up of two relatively narrow strips 13 and 14, preferably of spring metal, spaced from each other by means of a spacer 11' and secured together at one end 11 by any suitable means, such as welding.

The members 13 and 14 are spaced from each other by the spacer 11' to provide a channel or passage 12' for the transfer sheet 15 and a form sheet 6, as best shown in Figs. 8 and 9.

In using the holder for attaching a transfer sheet on the strip 14 and also for inserting the upper sheet 6 of the form 3 between the strips 13 and 14, the strips 13 and 14 may be spread apart, as indicated by dotted lines in Fig. 1.

A transfer sheet 15 is provided near its top edge 16 with a plurality of paired slots or openings 17. The transfer sheet 15 is secured on the holder 12 by inserting the blade or strip 14 in the openings 17, as indicated in Fig. 5. The portion 18 of the transfer sheet 15 above the blade 14 is folded over the blade 14 on the line 19, as

indicated in Figs. 3, 5, and 8. The blade, or strip 14, is shorter than the blade or strip 13, as indicated in Figs. 1, 5, and 9, and when the blade 14, with the transfer sheet 15 attached thereon, is inserted between the sheets 6 and 7 of the form 3, the end 20 of the blade 14 clears the fold 5 of the form 3, as indicated in Fig. 9. The end 11 of the holder 12 and the end 10 of the blade 13 are then inserted in the openings 9 of the ears 8. With the holder 12 thus engaged in the ears 8 of the writing plate 1, the transfer sheet is securely held in proper position, relative to the writing plate and the forms, and the form 3 is guided and held against the transfer sheet by the blade 13.

With the holder 12 and transfer sheet 15 in position and firmly held by engagement of the holder 12 in the lugs 8, the form sheets 6 and 7 may be pulled downwardly on the writing plate 1 to bring a second set of forms through the slot 2 and onto the writing plate 1 in proper relation to the transfer sheet 15. In this operation, the upper sheet 6 passes through the channel 12' between the upper blade 13 of the holder 12 and the transfer sheet 15, and the lower sheet 7 passes between the writing plate 1 and the folded portion 18 of the transfer sheet 15 which is secured on the blade 14. As the end 20 of the blade 14 clears the fold 5 of the form 3, no resistance, or interference, is presented to such a movement of the form 3 by the holder 12.

Whereas, I have shown and described a single holder in co-operative relation with a single transfer sheet and a single set of forms, it will be understood by those skilled in the art to which this invention appertains that any multiple of form sets and transfer sheets may be conveniently used, a holding device being used with each transfer sheet.

40. What I claim is:—

1. A holder for transfer sheets comprising, two strip members of flat spring metal and having the same width, one of said members being positioned above the other and spaced therefrom, a spacer member between said strip members at one end of said strip members, said strip members and said spacer member being fixedly secured together to provide an unitary structure.

2. A holder for transfer sheets comprising, two flat strip members of spring metal, one of said members overlying the other, a spacer member between said strip members at one end thereof, said strip members and said spacer member being relatively similar in thickness and welded together to provide an unitary structure, one of said strip members being longer than the other, whereby the end of said longer member opposite the spacer member extends beyond the corresponding end of the shorter member.

3. A holder for transfer sheets comprising, upper and lower flat strip members of spring metal, the upper member being superposed on the lower member and formed with tapered end portions,

the lower member being formed with a tapered end portion and a rounded end portion, the tapered end portion of said lower member being fixedly secured to a tapered end portion of said upper member, said lower member being shorter than said upper member, whereby the tapered end of said upper member opposite the secured end extends beyond the rounded end of said lower member.

4. In combination, in a counter sales book for use with zig-zag folded forms, a writing plate provided with upwardly extending oppositely positioned ears, a transfer sheet holder comprising, a spring blade removably engaged in said ears and a second spring blade shorter than the first- 15 named blade and having an end thereof fixedly secured on an end of said first-named blade.

5. In combination, in an autographic register device for use with zig-zag folded forms, a writing plate provided with upwardly extending oppositely disposed apertured ears, a transfer sheet holder comprising a blade of spring metal, a second blade superposed on the first-named blade and longer than the first-named blade, said first and second blades being spaced from each other 25 and fixedly secured together at one end, said second blade being removably secured in said ears.

6. In a book device for use with zig-zag folded forms, a writing plate on which a set of said forms may be positioned and provided with oppositely positioned ears, a transfer sheet inserted between the upper and lower leaves of said form set and provided with spaced openings, a holder for said transfer sheet comprising a blade member engaged in said spaced openings and extending beyond one side edge of said transfer sheet and a second blade member fixedly secured to said first-named blade member, superposed thereon, and spaced therefrom, and engaged in 40 said ears, whereby said transfer sheet is fixedly secured above said writing plate between said ears and between the leaves of said form set and said form set is slidably guided on said writing plate with its upper leaf between said transfer 45 sheet and said second blade.

7. In combination in a counter sales book, a writing plate provided with oppositely upwardly extending apertured ears, a transfer sheet holder comprising, a spring blade removably engaged in said ears, a second spring blade shorter than said first-named blade, a spacing member positioned between said blades with the adjacent ends of said blades and said spacing member flush, said blades and said spacing member being welded 55 together to provide an unitary structure.

8. A holder for transfer sheets comprising two flat strip members of spring metal and having the same width, said members being spaced from each other and fixedly secured together at one 60 end only, one of said members being secured over the other.

EDWARD HANO.
